UNITED STATES PATENT OFFICE.

CARL RICHARD JERNBERG AND MODESTE A. METZGER, OF CHICAGO, ILLINOIS, AND
EDWARD LARSON, OF INDIANA HARBOR, INDIANA, ASSIGNORS TO STANDARD
FORGINGS COMPANY, OF CHICAGO, ILLINOIS, A CORPORATION OF ILLINOIS.

ATTACHMENT FOR DRAFT RIGGING.

Application filed November 30, 1921. Serial No. 518,863.

To all whom it may concern:

Be it known that we, CARL RICHARD JERNBERG, MODESTE A. METZGER, and EDWARD LARSON, citizens of the United States, said 5 Jernberg and Metzger residing at Chicago, in the county of Cook and State of Illinois, and said Larson residing at Indiana Harbor, Lake County, Indiana, have invented 10 Attachments for Draft Rigging, of which the following is a specification, reference being had to the accompanying drawings and to the reference characters marked thereon, which form a part of this specification.

15 This invention relates to the art of draft rigging for railway cars, and more particularly to the means for connecting the yoke and the car coupler.

20 One of the objects of our invention is to produce a forged steel yoke and forged steel yoke heads so designed as to be relatively cheap to construct and of great strength, and yet be as light as possible. That is to 25 say, being so designed as to have abundance of metal where needed and less metal where same may be spared, without impairing the efficiency of the device as a whole.

Another object of our invention is to produce complementally engaging parts on the 30 yoke and on the yoke heads, so designed as to be quickly and readily assembled in operative position; and when so assembled, shall be so interlocked as to make in effect 35 a substantially solid union of the two.

To secure these objects and the desired advantages therefrom so that the yoke and head may be applied to known and standard draft rigging units and car couplers, has 40 not been a matter of easy accomplishment in forged steel, but are secured by our invention. To this end, our invention consists in the devices and combination of devices herein illustrated, described and more particularly pointed out in the appended claims.

45 In the drawings:

Fig. 1 is a plan view of a device embodying our invention, showing it attached to the shank of a car coupler and surrounding a conventional draft gear unit.

50 Fig. 2 is a side view of the same, partly in section, and showing in addition supporting straps, a strike post and the end beam or channel of a car construction.

Fig. 3 is a perspective view, enlarged, of 55 the yoke proper.

Fig. 4 is a perspective view of one of the yoke heads.

Fig. 5 is a perspective view of the yoke and yoke heads, showing one yoke head 60 seated and the other in the act of being seated.

Fig. 6 is a sectional detail showing the relation of the engaging complementary surfaces of the yoke and yoke head, the sections 65 being in the plane indicated by the dotted line 6—6 of Figs. 1 and 7.

Fig. 7 is a similar view of the same parts, the section being taken on the plane indicated by the dotted line 7—7 of Figs. 2 and 6. 70

The yoke is indicated as a whole by the letter A and the yoke head by the letter B. C indicates the shank end of a conventional car coupler; D, D' parts of a draft gear unit, and E stops usually attached to parallel sills of a car construction and against the inner end of which the part D' of the draft gear unit abuts. F, F, are horizontally disposed supporting straps of the car structure, usually attached beneath the sills 80 of the car. G is a conventional strike plate upon the end beam or channel H, and J is a key or pin of the M. C. B. type.

The draft gear unit D, D' may be of any conventional type; they may, for example, 85 be of the construction shown in the Christy Patent No. 1,263,374, of April 13, 1918, where the housing of the member D is hollow and contains springs acted upon by triangular shaped wedges d. As this forms 90 no part of the present invention, reference may be had to the said Christy patent for further description; it being understood, however, that there is relative movement 95 between the parts D and D', both on the draft and the buff; the part D' and wedges d being pushed toward the part D on the buff, and the part D traveling longitudinally toward the part D' under draft of the 100 coupler yoke.

The yoke A is a U-shaped structure, composed of two parallel, thin, and relatively wide strap members, 1, 1, and a transverse integral end member 2, joined to the members 1, 1, at the rounded corners or margins 105 3. The forward end 4 of each strap member 1 is enlarged laterally so that its width is greater than the width of the strap 1.

At each side of the end 4 is a hook member 5. In rear of the end 4 and opposite each hook member 5, each edge 6 of the strap 1 is provided with a laterally projecting lug 7 having an inclined bearing surface 8.

Between the bearing surface 8 and the extreme end 9 of each hook member 5 is a recess indicated at 10. This recess is defined by the bearing surface 8 of the lug 7, the plane surface 11 of the end 4 and the curved surface 12 of the hook 5. On the inside of the ends 4, the surfaces are straight, coincident with the inner surfaces of the straps 1 and therefore parallel. On the outside of the ends 4, the metal is thickened over the hook members 5 by the bosses 13. The shape and configuration of these thickened parts or bosses 13 is such as to give the greatest strength where strength is required and yet the contour slopes and curves so as to provide no unnecessary weight of metal. The surfaces 11, 11, are parallel.

It will of course be understood that in use, the position of the parts is such that the coupling pin or key J extends in a horizontal position, rather than in a vertical position as is the case with some devices of this general character.

In order to connect this yoke A with the shank of the car coupler C, two heads B and the pin or key J are required. Each yoke head B is a plate provided with a transverse aperture or key-way 14. The key-way 14 is in what may be termed the forward portion of the head B and is an elongated slot corresponding in contour with the cross-sectional area of the key J, the latter being shown in position in Figs. 1 and 2.

Each yoke head B is provided with a pair of hooked members 15 adapted to engage the hook members 5, 5, of the yoke, each being provided with a straight engaging wall 16 and a curved surface 17, the latter terminating in a hook point or end 18. It will be noticed that the yoke heads B are of somewhat greater thickness than the thickness of the yoke members 1, but are of substantially the same thickness as the hooks 5 of the yoke. By reducing the thickness somewhat at the outer margin 19, 19, and in the center 20, back of the key-way 14, considerable metal is saved without weakening the heads. The surfaces or walls 16, 16, are parallel, as shown.

In Fig. 5 we have illustrated the method of interlocking the hooks 5 and 15. The head B is brought into juxtaposition, its forward end tipped so that the curved surfaces 17, 17, may be brought into contact with the curved surfaces 12, 12, of the hooks 5, then raised with a sort of rocking movement until the back edge or margin 21 of the head contacts with the lug 7, whereupon by further movement in the same direction,

the parts become engaged, as shown clearly in Figs. 1, 2, 6 and 7. In this engaged position, it will be noted that the inside flat surfaces of the heads B rest firmly upon the parallel surfaces or walls 11, 11, of the yoke, and the flat surfaces or walls 16, 16 rest firmly between the parallel inside wall surfaces of the yoke ends 4, 4.

It will also be noted that when the yoke heads B and the yokes are thus united, the outside or marginal parallel surfaces 22, 22, of the yoke hooks 5, 5, and the top surfaces 23 of the head hooks 15, 15, are in alignment and come nicely within the parallel inside surfaces of the stop E, E, or other conventional structure which may be employed as part of the draft gear rigging.

We recommend that our improved hooked yoke and yoke head be fabricated by forging and have designed the details of construction to that end. While some slight modifications may be made without departing from our invention, yet from successful experience we recommend the form shown as possessing great strength without embodying unnecessary metal, as available for relatively cheap cost of production, as not liable to be readily damaged or broken in use, and as possessing the very desirable useful function of properly distributing the metal so as to successfully take care of the stresses and strains of car service.

We claim as our invention:

1. The combination of a yoke and a pair of yoke heads, the forward end of each of the yoke arms being enlarged and provided with a rearwardly turned, outwardly extending, integral hook member, and each yoke head being provided with a forwardly turned hook member on its top and bottom margin; each hook member having a surface complementary to the surface of the yoke hook member with which it engages when the parts are assembled, and a horizontally disposed key way in each yoke head adapted to receive a key to lock the yoke heads and connected yoke to a car coupler.

2. The combination of a yoke and a pair of yoke heads having complementary and inter-engaging surfaces and means for locking same to a coupler, each arm of said yoke having a widened forward end provided with two rearwardly directed hook members and an integral lug on each side margin of each yoke arm opposite the hook member.

3. The combination with a pair of yoke heads, of a U-shaped yoke, each arm of which yoke has an enlarged forward end provided with two laterally disposed, integral rearwardly directed hook members and with an integral lug on each side margin of each arm near the hook member, the yoke heads and the yoke hook members having complementary engaging surfaces, each lug being provided with a forwardly and down-

wardly inclined bearing surface against which the rear marginal surface of the yoke heads will rest when the parts are assembled and means for locking the yoke heads to a coupler.

4. A draft gear yoke having each of its arms narrower and thinner than its forward end, hook members on each end, bosses on the outside of each hook member, and a lug projecting from the side margin of each arm member opposite the hook member on said margin, in combination with yoke heads having surfaces adapted for engagement with said lugs and hook members and means for securing the yoke heads to a car coupler.
5. A pair of yoke heads each provided with a forwardly directed hook member at its rear side margin, a boss on the outside of each hook member, curved bearing

surfaces on the hook members terminating in straight surface walls, an elongated slot key way aperture in each yoke head, the top and bottom longitudinal walls of which slot are parallel to each other and to the said straight surface walls, a yoke having on each of its ends hook members adapted to engagement with the yoke head hook members.

In testimony, that we claim the foregoing as our invention, we affix our signatures in the presence of two witnesses, this 22d day of November, 1921.

CARL RICHARD JERNBERG.
